CLAIM

The ornamental design for a set of road barrier and executive toy pieces, as shown and described.

DESCRIPTION

FIG. 1 is a front elevational view of a set of road barrier and executive toy pieces showing the present design;

FIG. 2 is a top view of the set of road barrier and executive toy pieces of FIG. 1;

FIG. 3 is an alternative, top view of the set of road barrier and executive toy pieces of FIG. 1;

FIG. 4 is a bottom view of the set of road barrier and executive toy pieces of FIG. 1;

FIG. 5 is a left side end view of the set of road barrier and executive toy pieces of FIG. 1;

FIG. 6 is a right side end view of the set of road barrier and executive toy pieces of FIG. 1;

FIG. 7 is a front prospective view of the set of road barrier and executive toy pieces of FIG. 1; and,

FIG. 8 is a rear prospective view of the set of road barrier and executive toy pieces of FIG. 1.
